UNITED STATES PATENT OFFICE

CHARLES A. WARDNER, OF BRUSHTON, NEW YORK.

TELEPHONE SYSTEM.

No. 849,032.

Specification of Letters Patent.

Patented April 2, 1907.

Application filed December 7, 1906. Serial No. 290,722.

To all whom it may concern:

Be it known that I, CHARLES A. WARDNER, a citizen of the United States, residing at Brushton, in the county of Franklin and State of New York, have invented certain new and useful Improvement in a Telephone System, of which the following is a specification, reference being had therein to the accompanying drawings.

10 My invention relates to telephone systems and the apparatus therefor; and the object of the invention is the provision of means whereby the talking capacity of a line is doubled, enabling two separate conversations to be carried on at the same time without interfering with each other. To attain this, I make one talking-circuit entirely metallic and the other grounded.

15 A further object of the invention is the provision of means to double the number of instruments on the line, which I attain by using a third wire operating in conjunction with the ground-circuit and a suitable switch and which is adapted to carry bells only. 20 Heretofore systems of this type have proved noisy; and there was such a quantity of cross-talk that many systems have had to be abandoned after installation.

25 With the present invention I not only do away with and obviate the difficulties heretofore encountered, but am able to use a greater number of instruments and at the same time provide means whereby parties having their telephones connected to ground are not disturbed by the ringing of parties connected metallic, and vice versa.

30 Specifically stated, my invention contemplates a system having an independent metallic circuit, a third wire associated with said metallic circuit, and a common ground return for two of said wires, so that talking can be carried on over the metallic circuit and over the ground-circuit, and by the addition of the third wire ringing-current can be 35 sent over two of the wires and over the third and the ground, which enables me to get just double the ringing facilities.

40 Further objects of the invention will be apparent when the appended specific description is read in connection with the accompanying drawings, in which—

Figure 1 is a side elevation of the hook and special switches with the inclosing casing broken away. Fig. 2 is a plan view of the

latch-plate associated with the hook and special switch-levers, and Fig. 3 is a diagrammatic view of the wiring of several substations on the circuit with the bells at station a' grounded.

Referring to the drawings, 1 and 2 represent the conductors of the metallic circuit, and 3 the supplemental conductor, which is used for bells only. Each substation is provided with the usual telephone-box E, to which are secured the terminal binding-posts 65 7, 8, and 9 for the wires 4, 5, and 6, which are tapped off the wires 1, 2, and 3, respectively.

Rigidly secured to the box or casing E is an arm 11, which is provided with a depending portion 12, adapted to receive the switch 70 contact-springs s , s' , s^2 , s^3 , and s^4 , which are adapted to be actuated by a switch-lever s^6 , pivoted upon the arm 11 and having a handle s^{10} projecting outside of the casing. This lever s^6 is normally held in raised position by 75 a spring s^5 , secured to the depending portion 12 of the arm 11 and bears against a lug on the under side of the lever. Springs s^6 and s^5 are separated from each other and held in this relation by suitable insulation, and 80 spring s^5 is connected to the operating-spring s^6 by suitable insulation. Pivoted to the casing E at w^2 is a hook-lever W, having at its upper end a hook w' , adapted to normally lie within the path of the switch-lever s^6 . 85 The lower end of said lever W is provided with a weight w^3 , having a cam-face w^4 adapted for engagement with the hook-lever h of the switch 11.

90 It will be seen that when the hook-lever h is depressed by reason of the receiver R being in place the hook end w' of the lever W is thrown out of the path of the switch-lever s^6 ; but when the switch-lever h is in raised position the hook end w' is in the path of the lever s^6 , so that it may engage said lever and hold it in depressed position, thus changing 95 the relation of switch-springs s , s' , s^2 , and s^3 , the relation of s^2 and s^3 remaining always the same. Normally when ringing and talking over the metallic conductors 1 and 2 the switch S and the hook-lever W play no part; but when it is ascertained that the metallic side of the line is being used and it is necessary to use the grounded circuit the receiver 100 is removed from the hook h , and upon finding that the metallic side is being used the switch-handle s^{10} is depressed, thus allowing 105

the hook w' to engage the lever s^0 and hold it in depressed position, by which action the system is changed from a metallic one to a grounded one. Thus instruments connected 5 ground on the circuit can be rung and talked to without interruption to any "metallic" conversation. The metallic ringing-circuit is traced as follows from the terminal binding-post 7: wire 13, 28, 29, thence through 10 switch-hook h , by wire 22, through ringer Q , wire 20, switch-springs s' and s , wire 14, terminal binding-post 8, wire 5, to conductor 2. The grounded ringing-circuit when the 15 switch-lever s^0 is depressed is traced as follows: from ground at station A, 32, 10, 15, s^2 , s' , 20, 24', 24, 27, g , 30, 28, 23, s^4 , s^3 , 17, 9, 3, and to the substation A' over wire 6, 9, 18, z' , y , Q , z , y' , 19, 10, 32, and ground.

The talking-circuit is traced as follows: 20 from wire 1 to 4, from terminal binding-post 7, wires 13, 28, and 29, switch-hook h , to wire 25 and the secondary i' of the coil I, to wires 26 and 24, to binding-post 24'. From thence it passes to switch-springs s' and s , wire 14, 25 terminal binding-post 8, and wire 5 to the conductor 2. The grounded talking-circuit is identical with the metallic one up to the binding-post 24', where it passes by way of switch-spring s' to the switch-spring s^2 , wire 30 15, terminal binding-post 10, and to ground through wire 32, the lever s^0 being depressed. I have provided the usual transmitter T, which is included within a local circuit embodying the primary i' of the induction-coil 35 I and the local battery B.

At each of the substations there are provided two clips y and z , connected permanently with each side of the ringer Q and having terminal tips adapted to removably 40 connect with the binding-posts 22' and 24' and also into the binding-posts y' and z' . The binding-post y' leads directly through wire 19 to the terminal 10 and wire 32 to ground, and the binding-post z' is connected 45 through wire 18, terminal 9, and wire 6 to the supplemental conductor 3. By this means the bells of any instrument can be changed from metallic to "grounded," and any subscriber can ring all other instruments on the line whose bells are grounded to the third wire by pressing down the lever s^0 while ringing. If the flexible cords y and z are in the binding-post 22' and 24', any 50 subscriber can ring all other instruments on the line whose bells are connected metallic by ringing in the ordinary way without depressing the lever s^0 .

In the system shown in Fig. 3 I have shown three stations, designated as A station, A' station, and A² station for convenience in referring thereto. In the general operation of the signaling devices of the system let it be assumed that a person at any 55 subscriber, as A², wishes to communicate with any other station—for instance, station

A. He first takes up the receiver from the switch-hook S and listens to ascertain whether or not the line is already employed by some other station. Finding the circuit free, he then operates the generator G in the ordinary manner to ring station A. This results in the ringing of all metallic bells, as follows: from contact g of generator G, wire 27, wire 24, binding-post 24', 20, s' , s , 14, 8, 5, 2, and to the subscribers' stations having their 70 bells connected metallic and over the substation-circuit, thus: 5, 8, 14, s , s' , 20, 24', Q, 22', 22, H, 29, 28, 13, 7, 4, and back over line-wire 1 to the wire 4, binding-post 7, 13, 28, 30, back to generator G; but as each subscriber has his own code-signal and as the generator is operated in a manner to correspond to station A all other stations will disregard the ringing of their bells and conversation can be carried on in the ordinary way. 80 If, however, the metallic line is being used and the person calling station A is in a hurry, he depresses the switch-lever s^0 after the receiver has been removed from the switch-hook h and releases it; but owing to the fact that the hook-lever W is not acted upon by the switch-lever h the hook w' thereof will engage the lever s^0 and hold it in depressed position until the receiver is again hung up, when the lever h' acts upon the cam w^4 of the 90 weighted end w^3 of the lever W and throws the hooked end w' out of engagement with the lever s^0 , which is now thrown to its original position by the spring s^5 . With the lever s^0 in depressed position the talking is 95 over the grounded circuit that interferes in no way with the talking or ringing of other telephones on the line over the metallic circuit. If the metallic line is busy and the subscriber at A² desires to call the subscriber at A, he rings over the metallic circuit in the regular way and by means of the code used gets the subscriber he wants. This results in all the metallic bells ringing and a slight buzz in the receivers of the metallic telephones at the substations which are 100 busy. This can be obviated in any well-known or suitable manner.

Instruments equipped with this invention can be used anywhere and in any way that ordinary bridging instruments can. When used as ordinary instruments on a single wire or grounded system, by the addition of another wire to make the line metallic the system can be used with all bells rung metallic, and the talking capacity will then be doubled, (one metallic and one grounded circuit.) By connecting half the bells metallic and half grounded by means of clips y z the system can now be used with only one (metallic) talking-circuit, but with double or split ringing-circuit, as half the substations can be rung metallic and half grounded by depressing handle s^{10} while ringing grounded. In this last case wire 4 must connect to both 110 115 120 125 130

terminal binding-post 7 and terminal binding-post 9. Thus main wire 1 takes the place of 1 and 3.

It will be seen by the above that the invention can be used without the third wire; but if it is desired to double both the talking capacity and the number of instruments the third wire must be used.

A telephone equipped with this invention can be used on any common metallic bridging-line to connect any one desired subscriber with the switchboard, so as to render absolutely private service without interfering with the regular service of the other telephones on the line, or any two subscribers can be equipped with this device on a common metallic bridging-line and can conduct their business privately in addition to using the rest of the line in the ordinary way, and, furthermore, a metallic bridging-line equipped with this invention, whether using two or three wires, can be switched onto a common grounded or single-wire bridging-line and hold conversation therewith without the use of a repeating-coil.

Having thus described my invention, what I claim, and desire to secure by Letters Patent, is—

1. A party-line telephone system, comprising a main circuit having two metallic conductors, a supplemental conductor, a common ground return for one or more of said conductors, and means whereby one of said conductors and the common ground return may be utilized for talking purposes while the main circuit is being used.

2. A party-line telephone system, comprising a main circuit having two metallic conductors, a supplemental conductor, a common ground return for one or more of said conductors, means for sending ringing-current over the main circuit, and means whereby ringing-current may be sent over the supplemental conductor and said ground return.

3. A party-line telephone system, comprising a main circuit having two metallic conductors, a supplemental conductor, a common ground return for one or more of said conductors, means for sending ringing-current over said main circuit, and means whereby ringing-current may be sent over one of said conductors and the common ground return.

4. In a party-line telephone system, the combination with a main circuit comprising two metallic conductors, of a supplemental conductor, a common ground return for one

or more of said conductors, and means whereby the normal talking-circuit can be changed from metallic to grounded.

5. In a party-line telephone system, the combination with a main circuit having two metallic conductors, of a supplemental conductor, a common ground return for one or more of said conductors, means for changing the normal talking-circuit from metallic to grounded, and means for holding said last-named means in operative position during conversation.

6. In a party-line telephone system, the combination with a main circuit comprising two metallic conductors, of a supplemental conductor, a common ground return for one or more of said conductors, means for changing the talking-circuit from a metallic to a grounded one comprising a switch, and automatic means for holding said switch in operative position during conversation.

7. In a party-line telephone system, the combination with a main circuit comprising two metallic conductors, of a supplemental conductor, a common ground return for one or more of said conductors, a switch for changing the normal talking-circuit from a metallic to a grounded one, means for holding said switch in operative position, and means for automatically releasing said switch.

8. In a party-line telephone system, the combination with a main circuit comprising two metallic conductors, of a supplemental conductor, a common ground return for one or more of said conductors, a switch for changing the normal talking-circuit from a metallic to a grounded one, a weighted hook-lever adapted to engage said switch to hold it in operative position, and a receiver-lever adapted to release said weighted lever so that the switch may be returned to its normal position.

9. A party-line telephone system, comprising a main circuit having two metallic conductors, a supplemental conductor, substations connected to said conductors, ringers at the substations, and means for changing the ringers from the metallic circuit to one of the conductors and a common ground return.

In testimony whereof I have affixed my signature in presence of two witnesses.

CHARLES A. WARDNER.
